DRESSER

Aldor Odessa Belanger, Mattawa, Ontario,
Canada*Application May 20, 1949, Serial No. 2,782
In Canada February 12, 1949*Term of patent 7 years*(Cl. D33—6)*To all whom it may concern:

Be it known that I, Aldor Odessa Belanger, a citizen of the Dominion of Canada, and a resident of Mattawa, in the Province of Ontario, Canada, have invented a new, original, and ornamental Design for a Dresser, of which the following is a specification, reference being had to the accompanying drawing, forming part thereof.

The figure represents a perspective view of a dresser showing my new design.

The obscured end portions are similar to those shown.

I claim:

The ornamental design for a dresser, as shown and described.

ALDOR ODESSA BELANGER.
